Barnet L. Abrams Inventor

By his Attorney

Martin Jachimson

UNITED STATES PATENT OFFICE.

BARNET L. ABRAMS, OF NEW YORK, N. Y.

EMERGENCY SOLE.

Application filed July 21, 1924. Serial No. 727,268.

To all whom it may concern:

Be it known that I, BARNET L. ABRAMS, a citizen of the United States, and resident of New York, in the county of New York 5 and State of New York, have invented certain new and useful Improvements in Emergency Soles, of which the following is a specification.

This invention relates to improvements in 10 foot-wear particularly in the soles thereof, and it is the principal object of the invention to provide an elastic attachment for the soles, so-called emergency-sole, particularly well adapted for use by farmers, 15 truck gardeners, and other persons living in camps or residing at a considerable distance from a cobbler or shoe-maker's shop.

Another object of the invention is the provision of an emergency-sole which can readily be attached to any shoe without the aid 20 of machinery and thread.

A further object of the invention is the provision of an emergency-sole which can be conveniently carried along and used if 25 emergency so requires.

With these ends in view the novel emergency-sole consists of a pad of plastic material preferably rubber to which a stiffening plate preferably made of metal is secured 30 by vulcanizing or otherwise, provided with means for readily attaching the pad to the shoe to cover the broken or otherwise damaged original sole thereof.

The invention furthermore relates to an 35 emergency-sole pad provided with suitable stiffening means ensuring the holding of nails or other fastening means for securing the emergency-sole to a boot or shoe.

These and other objects of my invention 40 and advantages thereof will become more fully known as the description thereof proceeds, and will then be particularly pointed out in the appended claims.

In the accompanying drawing, forming a 45 material part of this disclosure:

Figure 1 is a side elevation of a shoe equipped with an emergency-sole constructed according to the invention.

Figure 2 is a bottom plan view, partly 50 broken away to show the interior construction.

Figure 3 is a top plan view of a stiffening and holder plate used in the construction of the emergency-sole.

Figure 4 is a cross-section on line 4-4 55 of Figure 1.

Figure 5 is a plan view of a modified form of emergency-sole, and

Figure 6 is a longitudinal section on line 60 6-6 of Figure 5.

The emergency-sole or shoe-attachment of the construction illustrated in Figures 1, 2, 3 and 4 comprises an elastic pad 10 to which is vulcanized or otherwise secured a metal plate 11 having a plurality of comparatively large openings 12 presenting substantially the appearance of a grating and also provided with a plurality of larger and smaller holes 13 and 14 respectively along its outer margin and the longitudinal 70 bar 15 and cross-bars 16 forming the grating.

Along its outer edges the plate 11 is equipped with a plurality of marginal prongs or teeth 17 adapted to be bent over 75 and to firmly engage the welt 18 of the shoe or boot, while the inner end edge of the plate is provided with a plurality of smaller teeth 19 and is adapted to be bent upon itself to engage with its teeth the end of the shoe 80 sole. Nails 20 or similar suitable and customary fastening means may be driven through the pad 10 and the plate 11 into engagement with the shoe sole and to be clinched at their inner ends as shown in 85 Figure 4.

The modified form of the emergency-sole illustrated in Figures 5 and 6 consists of a rubber pad 21 to which is vulcanized or otherwise secured an inner stiffening plate 22 provided with a plurality of larger and smaller nail holes 23 along its marginal edges or on its longitudinal bar 24 or cross-bars 24'. The outer contour of the pad is shaped to conform to the shape 95 of the customary shoe-sole.

It will be understood that the nails used are of larger diameter than the holes in the plate and will therefore, when driven home bulge the plate around the nails so 100 that the latter are firmly held by their frictional engagement with the plate and not liable to work out.

The operation of my device and the manner of its use will be completely and readily understood without further explanation from the above description and the drawing, particularly Figure 1 thereof, and it will be clear that any suitable means may be used to secure the pad to a sole, and that 110 changes may be made such as fall within the scope of the appended claims without

deviating from the scope and spirit of my invention.

Having thus described my invention, what I claim as new, and desire to protect 5 by Letters Patent is:

1. An emergency-sole comprising an elastic pad, stiffening means secured thereto, and means on said stiffening means for permitting an attachment of said emergency-sole 10 by bending said means around the outer edge of said sole to form a rim for the same outside of the edge portion of said sole.
2. An emergency-sole comprising an elastic pad, a metallic, perforated stiffening 15 means having a plurality of openings therein secured to said pad, and a plurality of holding means on said stiffening means for allowing a ready attachment of said emergency sole to a piece of foot-wear said holding means being so disposed, that they form the outer edge of the sole when bent into holding position.
3. An emergency-sole comprising a pad having substantially the shape of a shoe- 25 sole, a perforated stiffening plate vulcanized in said pad allowing fastening means to be passed through the perforations in said plate into the shoe-sole to secure the emergency-

sole thereto, and means on said stiffening plate for readily attaching and firmly se- 30 curing the whole to a shoe.

4. An emergency-sole comprising a pad of elastic material, a perforated stiffening plate secured in said pad allowing nails to be passed through the perforations in 35 said plate into the shoe-sole and to be clinched therein, and a plurality of prongs formed along the outer margin of said plate adapted to be bent upon the welt of the 40 shoe for securing the whole thereto.

5. An emergency-sole comprising an attachment pad of rubber, a metal stiffening plate secured therein, said plate having a plurality of wide openings therein to form a grating having longitudinal and cross-bars 45 provided with perforations, allowing fastening means to be passed through these perforations, marginal prongs formed on the stiffening plate, and teeth formed at its end adapted to be bent for engagement with the 50 shoe sole for firmly holding the emergency sole thereto.

Signed at New York, in the county of New York and State of New York, July A. D. 1924.

BARNET L. ABRAMS.
